METALLURGICAL APPARATUS FOR TREAT-
ING TEST SPECIMENS

Henry G. Keshian, Waterbury, Conn.

Application September 30, 1949, Serial No. 118,987

9 Claims. (Cl. 73—15.6)

1

The present invention relates in general to metallurgical apparatus and more especially to apparatus for subjecting solid metal test-specimens to successive treatments simulating actual operating conditions.

An object of the invention is to provide superior apparatus for treating solid metal test-specimens.

A further object of the invention is to provide solid metal test-specimen treating-apparatus of simple, durable and relatively-economical construction.

A still further object of the invention is to provide apparatus for repeatedly subjecting a plurality of solid metal test-specimens to temperature changes and pressures or stresses encountered under normal operating conditions.

A still further object of the invention is to provide solid metal test-specimen treating-apparatus which may be used selectively for subjecting test-specimens to the destructive forces to which stamping-die alloys, extrusion-die alloys, casting-die alloys, and similar die alloys are subjected when in use.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a side elevation partly in section of the improved apparatus of this invention for treating solid metal test-specimens;

Fig. 2 is a plan view of the apparatus of Fig. 1; Fig. 3 is an enlarged fragmentary front elevation of the test-specimen carrier of the apparatus of this invention, showing a section of the carrier on line 3—3 of Fig. 1;

Fig. 4 is an end elevation of the pressure-applying means of the apparatus on section line 4—4 of Fig. 1; and

Fig. 5 is a broken enlarged perspective view of the test-specimen mounting-ring of the carrier. In brief, the metallurgical apparatus of this invention is designed to subject a plurality of hard metal test-specimens repeatedly to temperature changes and stress in a predetermined sequence and for a given length of time, to simulate the destructive forces to which stamping-die alloys, extrusion-die alloys, and similar die alloys are normally subjected in use. After the test-specimens have been so treated, they are then etched and examined microscopically or by means of a

2

microscope, to determine how well a given test-specimen has resisted pitting, ridging, erosion, and the formation of insipient fractures or minute fissures.

5 The invention is carried out by the exemplary embodiment thereof shown in the drawings, wherein the test-specimen treating-apparatus comprises a substantially rectangular box-like base-member indicated generally at 10, having 10 test-specimen carrier-means indicated generally at 11 mounted thereon at one end thereof and stress-applying means indicated generally at 12 mounted at the opposite end thereof and in alignment with the carrier-means 11.

15 The substantially rectangular box-like base-member 10 may be constructed in any suitable manner and is preferably a welded metal structure embodying a flat substantially rigid bottom plate 13 on which is mounted a preformed inverted cover-like member comprising a flat top plate 14, side walls 15—15, and an end wall 16, the bottom edges of the side walls and end wall being welded or otherwise secured to the upper surface of the bottom plate 13. A separate plate

20 17 forms the end wall of the box-like member opposite its end wall 16, the plate 17 being suitably welded to the upper surface of the bottom plate 13 and to the underside of the top plate 14 of the cover inwardly of the corresponding end thereof, as shown especially well in Fig. 1. An aperture 18 is provided in the end wall 16 to give access to the interior of the box-like base-member, whereby a heat-exchanging fluid bath, such as indicated generally at 19 and hereinafter described, may be inserted therein. In the present embodiment, the fluid bath 19 comprises a

25 vessel for holding a body of liquid 20 which, for certain uses of the apparatus, may comprise water, oil, or the like, and which for other uses of the apparatus, may comprise a molten metal. 30 Associated with the fluid bath 19 is a heating-element 21, the latter being preferably an electric immersion-heater adapted to be connected to a suitable power source (not shown).

35 Formed in the top plate 14 of the box-like body-member is a substantially rectangular slot 22 extending longitudinally thereof and coincident with its longitudinal axis, the width of the slot 22 being somewhat greater than the width of the fluid bath 19, as shown clearly in Fig. 2.

40 Secured on the top plate 14 on opposite sides respectively of its slot 22 are bearing-brackets 23—23 for rotatably supporting the corresponding ends of a transverse shaft 24 which supports 45 the specimen-carrier 11 for rotation in a substan-

tially vertical plane within the slot 22 of the body-member and immediately above the fluid bath 19.

Referring especially to Figs. 2, 3 and 5 as a preferred embodiment, the specimen-carrier comprises a wheel consisting of a substantially solid hub indicated generally at 25 having conical side walls between which is an annular raised substantially cylindrical surface of revolution 27 provided at its right-hand edge, as seen in Fig. 3, with an integral radially extending annular flange 28. The latter is provided with a plurality of threaded apertures 29 substantially equally spaced therearound, into which assembling-bolts 30 are threaded for removably securing the test-specimens 31 and a test-specimen mounting-ring 32 thereto.

As shown especially well in Figs. 3 and 5, the test-specimen mounting-ring 32 is an annulus, the inside diameter of which corresponds substantially to the diameter of the cylindrical surface of revolution 27 of the hub, so that the annulus may fit snugly thereon, as shown clearly in Fig. 3, the outside diameter of the annulus corresponding substantially to the diameter of the annular flange 28 of the hub. As indicated in Fig. 5, the annulus or mounting-ring 32 is substantially rectangular in cross section and provided on its inner face with a plurality of rectangular grooves 33 substantially U-shaped in cross section, the longitudinal axes of the U-shaped grooves extending radially of the ring. Formed in the center of each groove 33 is a substantially smooth-bored aperture 34 for accommodating the shank of one of the aforesaid assembling-bolts 30. In this regard, each pair of apertures 34 of the mounting-ring is spaced apart a distance equal to the distance between each pair of apertures 29 of the annular flange 28, whereby on assembling the mounting-ring on the hub 25, the respective apertures of the ring and flange may be aligned to receive the assembling-bolts 30.

The test-specimens 31 are preferably rectangular heat-treated solid metal blocks, the inner ends of which are dimensioned to fit snugly in the U-shaped grooves of the mounting-ring, each test-specimen being provided with an aperture 35 through its inner end to receive an assembling-bolt 30. Thus, with the mounting-ring assembled on the hub 25 of the carrier 11 and oriented so as to align its bolt-holes with the bolt-holes of the annular flange, the inner ends of the solid metal test-specimens may be inserted into the U-shaped grooves of the mounting-ring whereupon by passing the assembling-bolts 30 through the aligned apertures of the mounting-ring and test-specimens and into the flange 28, the mounting-ring and its test-specimens are firmly secured on the hub 25 with the test-specimens projecting outwardly substantially radially therearound.

Mounted on the top of the box-like body-member on opposite sides respectively of the test-specimen carrier 11, are arcuate burners 36-36 which are substantially concentric to the loci of the outer ends of the test-specimens 31, each burner having combustion-apertures 37 on its inner face adapted to direct flames against the corresponding sides of the test-specimens as the latter are rotated by the carrier 11 between the arcuate burners, in the manner hereinafter described. A combustible mixture for producing flames at the combustion-apertures 37 of the burners is fed to the lower end of each burner by piping which is indicated generally at 38, and 75

connected to a common supply-pipe 39, the piping 38 and supply-pipe 39 being supported on and extending substantially transversely of the left-hand end of the box-like base-member.

The stress-applying means 12 of the apparatus is mounted on the top of the box-like base-member substantially opposite the test-specimen carrier 11, and as shown especially well in Figs. 1, 2 and 4 comprises a substantially rectangular yoke indicated generally at 40, each arm 41 of which has a longitudinal tongue 42 on its outer face substantially rectangular in cross section and adapted to slidably engage in a longitudinal substantially U-shaped guide-groove 43 formed on the inner face of a yoke-guiding block 44 secured by means of bolts 45 or equivalent fastening-means on the top of the body-member longitudinally thereof and adjacent its corresponding outer edge. The yoke 40 is thus adapted to move longitudinally to and away from the test-specimen carrier 11. Supported by the arms 41-41 of the yoke for rotation in a substantially vertical plane in the slot 22 of the body-member is a stress-applying wheel or pressure-wheel 46, the shaft 47 of the wheel being journaled at its opposite ends substantially transversely of the slot 22, as shown in Fig. 4, and in the axially aligned apertures 48-48 respectively in the ends of the yoke-arms 41-41. The pressure-wheel 46 comprises preferably a solid metal disk and as mounted thusly in the yoke, the vertical plane of the pressure-wheel 46 lies in the vertical plane of the test-specimen carrier 11.

Suitable adjusting-means are provided for moving the yoke to and from the carrier, thereby both to engage the periphery of the pressure-wheel 46 against the outer end of the test-specimens of the carrier under varying degrees of pressure and to withdraw the pressure-wheel therefrom. To these ends, a relatively long screw-bolt 49 is slidably engaged at its inner end in a central aperture of the crossbar 50 of the yoke, the inner extremity of the screw-bolt 49 projecting through the crossbar of the yoke and having a nut-and-washer assembly 51 thereon to prevent the bolt from being withdrawn from the aperture in the crossbar 50 of the yoke. The shank of the screw-bolt 49 extends outwardly to the right, as seen in Figs. 1 and 2, and is provided with an externally threaded shouldered enlargement 52. The externally threaded enlargement 52 of the screw-bolt is adapted to be threadedly engaged in an internally threaded aperture of a block 53 secured on the overhanging end of the top plate of the base-member, the outer extremity of the externally threaded enlargement terminating in a squared head 54 for application of a wrench or handle (not shown) for turning the screw-bolt. By turning the latter in a counterclockwise direction, the screw-bolt 49 will positively draw the slidable yoke 40 outwardly, thereby withdrawing the pressure-wheel 46 from engagement with the inner ends of the test-specimens of the carrier.

In order to slide the yoke inwardly, so as to urge the pressure-wheel against the outer ends of the test-specimens of the carrier, a coil spring 55 is mounted on the shank of the adjustable screw-bolt between the shoulder 56 thereof and the outer face of the crossbar 50 of the yoke, the coil spring thereby serving to transmit the longitudinal inward movement of the shoulder 56 of the screw-bolt to the crossbar 50 as the screw-bolt is rotated in a clockwise direction. Thus, the pressure-wheel 46 may be moved inwardly

to a position to engage against the ends of the test-specimens of the carrier. It will be clear that, by using the coil spring 55 to transmit the inward movement of the screw-bolt to the yoke 40, the pressure-wheel 46 will make resilient engagement with the ends of the test-specimens and that the pressure applied thereto by the pressure-wheel may be varied by rotating the screw-bolt. As shown especially well in Fig. 1, the shaft of the pressure-wheel is disposed in the horizontal plane of the coil spring and slightly below the horizontal plane of the carrier-shaft so that the force applied by the pressure-wheel against the test-specimens acts in a horizontal plane coincident with the initial point of engagement of each test specimen with the pressure-wheel, which engagement is substantially tangential to the periphery of the pressure-wheel, as illustrated in Fig. 1.

In order that an accurate measure may be made of the pressure being applied by the pressure-wheel to the ends of the test-specimens, a ring 57 is slidably mounted on the shank of the screw-bolt between its annular shoulder 56 and the corresponding end of the coil spring 55, the ring being provided with an upstanding index-finger 58 adapted to engage in a narrow guide-slot 59 extending longitudinally of a cylindrical sleeve 60 which encases the coil spring 55 and is secured by an annular flange 61 to the outer face of the yoke-crossbar 50. Suitable indicia 62 is provided on the upper surface of the sleeve 60, along the edge of its guide-slot 59, by which the position of the index-finger 58 may be identified. By calibrating the indicia 62 of the guide-slot in units of force, a measure of the pressure being applied to the ends of the test-specimens by the pressure-wheel 46 for any setting of the screw-bolt may be determined.

In using the apparatus for subjecting test-specimens to conditions of heat and pressure simulating those to which the alloy of a stamping-die is subjected, the heat-exchanging fluid bath 19 is filled with a coolant—preferably cold water. The burners 36 are then turned on and the carrier, including its radially disposed test-specimens, is rotated relatively slowly by suitable drive-means (not shown) in a clockwise direction, as seen in Fig. 1. Thus, the test-specimens 31 are heated during the first portion of their travel cycle by the burners to a relatively high temperature comparable to the temperature reached in a stamping-die. Thereafter, the outer ends of the test-specimens are subjected during another portion of their travel cycle to pressure comparable to the pressure used in die-stamping operations, and thereafter the test-specimens are cooled during still another portion of their travel cycle in the water bath 19. This cycle of treatments is repeated for a predetermined number of times on each respective test-specimen, after which each specimen is removed from the carrier, by withdrawal of the assembly-bolts 30, and examined in any well-known manner for evidences of pitting, ridging, incipient fractures, and other indications of breakdown.

In the present embodiment, the carrier 11 is adapted to support as many as eighteen test-specimens, and hence a relatively-wide selection of alloys may be tested simultaneously and thereafter examined to determine the suitability of each alloy for stamping-dies.

It is also within the purview of the invention to utilize the same apparatus for subjecting test-specimens to conditions wherein dies are sub-

jected to erosion from contact with molten metal, as for example, dies used in die casting and in extrusion operations. To this end, the cold water 20 of the fluid bath 19 is replaced by a body of molten metal such as, for example, molten aluminum, zinc, or the like, which is kept in a liquid condition by means of the immersion-heater 21. In order to simulate die casting and extrusion die conditions, the carrier 11 is rotated in a counterclockwise direction, as seen in Fig. 1, to immerse the test-specimens successively in the body of molten metal. Pressure is then applied to successive test-specimens of the carrier by the pressure-wheel. For simulating extrusion die conditions, the pressure applied will be considerable, whereas when simulating die-casting conditions, the pressure applied, if any, will be relatively small. Thereafter, the test-specimens are cooled. The cooling of the test-specimens may be done simply by rotating the specimens through the surrounding air, the burners being shut off; or cooled air may be delivered to the burners and fed from the combustion-apertures thereof to opposite sides respectively of the test-specimens as the latter are rotated between the burners, thereby cooling the test-specimens more rapidly. After repeating this cycle of treatments a predetermined number of times, the test-specimens are removed from the carrier and examined to discover evidences of breakdown and, in particular, the erosion effect of the hot metal on the test-specimens.

It will be understood that the alloy-treating cycles of the apparatus of this invention may be varied to accord with the conditions under which various types of dies are used, the apparatus being adapted to test alloy specimens, not only for dies to be used in stamping, extrusion and die-casting operations, but also for forging dies, dies for continuous casting, and draw dies.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. Specimen-testing apparatus for repeatedly subjecting a plurality of metal test-specimens to temperature variations and to stress, said apparatus comprising in combination: a base, an endless carrier mounted on said base and constructed and arranged to support a plurality of metal test-specimens, heating-means located adjacent a portion of the travel cycle of said test-specimens to heat said specimens, means on said base arranged to apply stress to said test-specimens during another portion of their travel cycle, and drive-means arranged to continuously move said carrier so as to subject said test-specimens repeatedly and successively to said heating-means and to said stress-applying means.

2. Specimen-testing apparatus for repeatedly subjecting a plurality of hard metal test-specimens to temperature variations and pressure, said apparatus comprising in combination: a base; an endless carrier mounted on said base constructed and arranged to support a plurality of hard metal test-specimens; means arranged to heat said test-specimens during a portion of their travel cycle; means arranged to cool said test-specimens during another portion of their travel

cycle; means on said base arranged to apply stress to said test-specimens during still another portion of their travel cycle; and drive-means arranged to continuously move said carrier to carry said test-specimens repeatedly into engagement successively with said heating-means, said stress-applying means and said cooling-means.

3. Specimen-testing apparatus for repeatedly subjecting a plurality of hard metal test-specimens to temperature variations and pressure, said apparatus comprising in combination: a base; an endless carrier mounted on said base constructed and arranged to support a plurality of hard metal test-specimens; means on said base arranged to heat said test-specimens during a portion of their travel cycle; means on said base arranged to cool said test-specimens during another portion of their travel cycle; means on said base arranged to apply stress to said test-specimens during still another portion of their travel cycle; drive-means arranged to continuously move said carrier to carry said test-specimens repeatedly into engagement successively with said heating-means, said stress-applying means and said cooling-means; and means arranged to adjust the stress applied to said test-specimens by said stress-applying means.

4. Specimen-testing apparatus for repeatedly subjecting a plurality of hard metal test-specimens to temperature variations and pressure, said apparatus comprising in combination: a base; an endless carrier mounted on said base constructed and arranged to support a plurality of hard metal test-specimens; means for heating said test-specimens during a portion of their travel cycle, said heating-means comprising burners mounted on opposite sides respectively of said carrier to heat the opposite sides of each test-specimen; means for applying stress to said test-specimens during another portion of their travel cycle, said stress-applying means comprising a wheel mounted on said base and resilient means arranged to urge said wheel into engagement with the ends of said test-specimens; means to cool said test-specimens during still another portion of their travel cycle; and drive-means arranged to continually move said carrier to carry said test-specimens repeatedly between the burners of said heating-means and into engagement with said stress-applying wheel and said cooling-means.

5. Specimen-testing apparatus for repeatedly subjecting a plurality of hard metal test-specimens to temperature variations and pressure, said apparatus comprising in combination: a base; an endless carrier mounted on said base constructed and arranged to support a plurality of hard metal test-specimens; means for heating said test-specimens during a portion of their travel cycle, said heating-means comprising burners mounted on said base on opposite sides respectively of said carrier to heat the opposite sides of each test-specimen; means for applying stress to said test-specimens during another portion of their travel cycle, said stress-applying means comprising a wheel mounted on said base and resilient means arranged to urge said wheel into engagement with the ends of said test-specimens; means on said base to cool said test-specimens during still another portion of their travel cycle; drive-means arranged to continually move said carrier to carry said test-specimens repeatedly between the burners of said heating-means and into engagement with said stress-applying wheel and said cooling-means; and adjustable mount-

ing-means associated with said resilient means to vary the pressure exerted by said wheel on the ends of said test-specimens.

6. Specimen-testing apparatus for repeatedly subjecting a plurality of hard metal test-specimens to temperature variations and pressure, said apparatus comprising in combination: a base; a test-specimen carrier comprising a rotatable hub mounted on said base and having a demountable test-specimen mounting-ring thereon arranged to secure a plurality of test-specimens on the periphery of said hub and extending radially therefrom; means for heating said test-specimens during a portion of their travel cycle, said heating-means comprising burners mounted on said base on opposite sides respectively of said carrier to heat the opposite sides of each test-specimen; means for applying stress to said test-specimens during another portion of their travel cycle, said stress-applying means comprising a wheel mounted on said base, resilient means arranged to urge the wheel into engagement with the ends of the test-specimens and adjustable mounting-means associated with said resilient means to vary the pressure exerted by said wheel against the ends of said test-specimens; means mounted on said base to cool said test-specimens during still another portion of their travel cycle; and drive-means arranged to rotate said carrier to carry the said test-specimens thereof repeatedly between said burners and into engagement with said stress-applying wheel and said cooling-means.

7. Specimen-testing apparatus for repeatedly subjecting a plurality of hard metal test-specimens to temperature variations and pressure, said apparatus comprising in combination: a base; an endless carrier comprising a rotatable hub mounted on said base and having a demountable test-specimen mounting-ring thereon arranged to secure a plurality of test-specimens on the periphery of said hub and extending radially therefrom; means for heating said test-specimens during a portion of their travel cycle, said heating-means comprising a pair of burners mounted on said base on opposite sides respectively of said carrier to heat the opposite sides of each test-specimen; means for applying stress to the ends of said test-specimens during another portion of their travel cycle, said stress-applying means comprising a yoke slidably mounted on said base for movement to and from said carrier and having a stress-applying wheel rotatably mounted thereon for engagement with the ends of said test-specimens, resilient means in engagement with said yoke and adjustable mounting-means associated with said resilient means arranged to urge said resilient means against said yoke to vary the pressure exerted by said wheel against the ends of said test-specimens; a water bath supported on said base to cool said test-specimens during still another portion of their travel cycle; and drive-means arranged to rotate said carrier to carry said test-specimens repeatedly between said burners and into engagement with said pressure-wheel and said water bath.

8. Specimen-testing apparatus for repeatedly subjecting a plurality of hard metal test-specimens to temperature variations and pressure, said apparatus comprising in combination: a base; an endless carrier mounted on said base constructed and arranged to support a plurality of hard metal test-specimens; means for heating said test-specimens during a portion of their travel cycle, said heating-means comprising a bath of

molten metal supported on said base; means mounted on said base to apply stress to said test specimens during another portion of their travel cycle; and drive-means arranged to continually move said carrier to carry said test-specimens repeatedly through said bath of molten metal into engagement with said pressure-means.

9. The combination defined in claim 8 which further includes means for cooling said test specimens during another portion of their travel cycle.
